UNITED STATES PATENT OFFICE.

JOHANN KEPPELER, OF BIRKESDORF, GERMANY.

LOOM FOR WEAVING WITH PILE WIRES.

Application filed April 10, 1926, Serial No. 101,096, and in Germany April 15, 1925.

In the known looms for weaving with pile wires, the motion of the pile wires is effected by a common loom drive designed to actuate all movable parts of the loom. 5 Owing to the fact that considerable resistances have to be overcome in starting the laying in and the withdrawing of the wires, it has hitherto been necessary to use for such looms a drive which is quite out of proportion to the average consumption of power.

The invention has for its object to provide a loom of the type stated which does no longer possess the said disadvantage, this 15 object being attained by providing a special drive for the wires which operates the wires either alone or in conjunction with the loom drive. In the last-said case the special wire drive and the loom drive act together for 20 starting the laying in and the withdrawing of the pile wires, while the wires are moved into their end positions by the loom drive alone. In case of electric driving, there may be used in accordance with the invention for 25 the operation of the wires either a constantly running electromotor or an electromotor which is connected with the current line by means of a drum switch during the starting movements and cut off from the current line 30 during the intervals.

Another object of the invention is to provide a clutch controlled by the loom drive and designed to couple the special wire drive with the wire actuating mechanism at suitable times for starting the wire movements.

If an independent electric drive is used for the pile wires, the wire motion is automatically stopped in the end positions of the wires by means of a brake magnet.

40 In the drawings:

Fig. 1 is a front elevation of a loom attachment according to the invention;

Fig. 2 is a similar elevation of a modified form of the attachment;

45 Fig. 3 is a diagram of one system of electric connections and

Fig. 4 is a diagram of another system of electric connections used in the attachment according to Fig. 1;

50 Fig. 5 is a diagram of the electric connections used in the attachment according to Fig. 2.

The loom and the wire mechanism are not shown because same may be of any suitable 55 well-known construction. The loom is supposed to be arranged at the right hand side

of the attachments illustrated in Figs. 1 and 2 of the drawing.

Referring now to the drawings, and more particularly to Fig. 1, 6 designates one of the 60 guide rails on which the slide 7 carrying the pile wires is moved to and fro by means of a rope 8 passing over idlers 9 and over a driving pulley 10. 11 is an electromotor designed to act on the pulley 10 in conjunction with the loom drive for starting the laying in and the withdrawing of the wires, while the latter are moved into their end positions by the loom drive alone. The shaft of the motor 11 carries a gear wheel 12 which meshes with a gear wheel 13 mounted for free rotation on the main shaft 14. The wheel 13 has rigidly connected with it a clutch member 15 adapted to be engaged and coupled with the shaft 14 by another clutch member 16 which is shiftable longitudinally on the shaft 14. Thus, when the clutch 15, 16 is thrown in the motor 11 will drive the shaft 14. The shaft 14 carries a 70 curved disc 17 the cam groove of which is engaged by a pin 18 fixed to a toothed sector 19 which is mounted for swinging motion at 75 20. The sector 19 meshes with a toothed wheel 21 which is fixed on the shaft 22 of the rope pulley 10. When the shaft 14 is rotating its disc 17 will impart to the sector 19, wheel 21 and pulley 10 partial rotations in opposite directions. These partial rotations are transmitted by means of the 80 rope 8 to the pile wires, laying the same in during the rotations of the pulley 10 in one direction and withdrawing them during the rotations of the pulley 10 in the opposite direction. 23 is the shaft of the loom drive which, when the loom is in operation, 85 constantly drives the shaft 14 by means of gear wheels 24, 25. The shaft 23 carries a curved disc 26 which is designed to actuate the movable clutch member 16 through the intermediary of levers 27, 27', 27'' and connecting rods 28, 28'. The cam groove of the curved disk 26 is of such a configuration 90 that it causes the clutch members 15, 16 to be engaged only at the beginning of the pile wire laying and withdrawing movements, while it causes the clutch members to be disengaged again after the wires have started 95 their respective movements. It will therefore be understood that the auxiliary motor 11 aids the loom drive in starting the laying in and the withdrawing of the wires.

100 During the operation of the loom, the

electromotor 11 may either be constantly running or it may be cut in and out at the proper times. In the first case the system of electric connections is as shown in Fig. 3, in which 29 is the main current feeding line, while 30 are branch conduits supplying the current to the motor 11 and 31 are conduits designed to supply current to the loom driving motor (not shown). The motors are cut in and out by a switch 32. In the second case the shaft 23 of the loom drive has operatively connected with it a drum switch 33 which is arranged in the branch conduits 30 for the motor 11, as shown in Fig. 4. This drum switch 33 is provided with two sets of contacts 34 and 35, one serving to cut in the motor 11 at the beginning of the laying in and the other serving to cut in the motor 11 at the beginning of the withdrawing of the pile wires. After the wires have started their respective movements, the current is cut off from the motor 11 at the switch drum 23 at the same time the clutch members 15, 16 are disengaged by the action of the curved disc 26.

According to the embodiment shown in Fig. 2, the pile wire drive is entirely independent from the loom drive. The electromotor 11, which is designed to operate the pile wires alone, is controlled by a drum switch 36 which is driven from a shaft 37 of the loom drive through the intermediary of gear wheels 38, 39. The drum switch 36 includes two sets of contacts 40, 41 one of which acts to cut in the motor 11 during the laying in of the wires, while the other acts to cut in the motor during the withdrawing of the wires, both sets of contacts operating in such a manner that the motor is cut out of circuit at the end of the respective wire movements. The driving mechanism of the pile wires is automatically stopped in the end positions of the wires by means of a brake magnet 42. The system of electric connections of the embodiment according to Fig. 2 is more particularly shown in Fig. 5.

The attachment forming the subject-matter of the invention may be applied to looms with individual drive as well as to looms with group drive.

Having thus described my invention, what I claim as new and desire to secure by Letters-Patent, is:—

1. In a loom for weaving with pile wires, a common loom drive and an auxiliary drive for operating the pile wires.

2. In a loom for weaving with pile wires, a loom driving mechanism, an auxiliary driving mechanism for operating the pile wires, and means actuated by the loom driving mechanism for throwing the auxiliary pile wire driving mechanism in and out.

3. In a loom for weaving with pile wires, a loom drive, an operating mechanism for the pile wires, an auxiliary electromotor for

driving the said operating mechanism, an electric drum switch arranged in the current supply lines of the auxiliary electromotor, means interposed between the loom drive and the drum switch for actuating this switch, a plurality of contacts in the drum switch for cutting the auxiliary electromotor in during the laying in and the withdrawing of the pile wires and for cutting the motor out at the end of the movements of the pile wires, and a brake magnet for stopping the operating mechanism of the pile wires at the end of the movements of the pile wires.

4. In a loom for weaving with pile wires, a loom drive, an operating mechanism for the pile wires, means for transmitting driving motion from the loom drive to the pile wire operating mechanism, an additional drive for the last said mechanism, means controlled by the loom drive for throwing the auxiliary drive in at the beginning of the movements of the pile wires and cutting it out again as soon as the pile wires have started their movements.

5. In a loom for weaving with pile wires, a loom drive, a pile wire operating mechanism, means for transmitting driving motion from the loom drive to the pile wire operating mechanism, an auxiliary electromotor, a coupling mechanism between the auxiliary motor and the pile wire operating mechanism, means between the coupling mechanism and the loom drive for the latter to actuate the coupling mechanism so as to be thrown in at the beginning of the pile wire movements and to be thrown out again during the continuation of these movements.

6. In a loom for weaving with pile wires, a loom drive, a pile wire operating mechanism including a main shaft, a toothed wheel gearing between the loom drive and this shaft for imparting rotation to the latter, another gear wheel mounted for rotation on the said shaft, an electromotor operatively connected with the last-said gear wheel, a clutch member rigidly connected with the gear wheel, another clutch member shiftably mounted on the said main shaft and adapted to enter into and out of engagement with the first-said clutch member, actuating means between the loom drive and the shiftable clutch member for throwing the clutch members into engagement at the beginning of the movements of the pile wires and thereafter disengaging them again, and an electric drum switch controlled by the loom drive and adapted to cut the said electromotor in at the beginning of the pile wire movements and to cut it out again after the pile wires have started their movements.

In testimony whereof I have signed my name to this specification.

JOHANN KEPPELER.
